UNITED STATES PATENT OFFICE.

FRED B. SAUNDERS, OF FRAMINGHAM, MASSACHUSETTS.

SASH HOLDER.

Application filed March 5, 1925. Serial No. 13,214.

This invention relates to slidable closures for windows and the like, and is particularly susceptible of embodiment in sash holders for window screens. One object of this invention is to provide a closure, or screen, which may be raised or lowered at any time with a minimum of effort, and without binding, irrespective of wear upon the bearing surfaces or of contraction or expansion of the supporting guides caused by climatic changes. Another object is the provision of such a closure having spring-tensioned rollers compensating for unevenness in the supporting guides, the tension of the spring being readily increased or decreased by a manual adjustment, accessible at all times; so that the closure, or screen, may be fitted to any of several windows in spite of slight variations in the distances between the supporting guides. A further object is the provision of a window screen of inexpensive, yet durable construction, which will effectively prevent the admission of insects, and which may be fitted to the weather strips of any window, without the employment of special supports.

One embodiment of the invention is shown in the accompanying drawing of a window screen, which is representative of any similar closure. In this drawing:

Fig. 1 is a partially broken elevation, showing portions containing the supporting rollers in sections;

Fig. 2 is an enlarged plan view partly in section, of one of the supporting rollers shown in Fig. 1;

Fig. 3 is an enlarged side view of the other roller shown in Fig. 1; and

Fig. 4 is a fragmentary section on the line 4—4 of Fig. 1.

The screen frame or sash 4, provided with the netting 5 in any suitable manner, is constructed to fit between the outer weather strips, or guides, 6, which form a part of the ordinary window casing, a space being provided between the side frames and said strips to prevent binding therebetween. In order to prevent the admission of insects through this space, a beading 7, extending from the outer surface of the screen frame, overlaps the weather strips.

The frame 4 is preferably supported within strips 6 by two pairs of rollers 8, which track in grooves 9, channeled in the strips. The groove 9 should be parallel to the outer surface of the strips and at such distance

therefrom that the overlapping beading 7 will meet the casing substantially flatwise, whereby the lip 7 will assist in maintaining the position of the rollers 8 within grooves 60 9 against inward movement of the sash 4, and will provide a tight closure between said sash and the guide strip 9 (see Fig. 4). The rollers on one side of the screen frame are preferably mounted in a carriage 10 which is fixed within a recess in the frame, one form of mounting being shown in Fig. 3, where the carriage is formed by bending a single sheet of metal to provide ears for the axle of the roller. 70

Transverse slots are provided in the opposite frame, wherein the roller and its mountings may be adjustably located at any desired position, relative to the casing strip 6, by turning a screw 11 in a threaded hole 75 in the plate 12 which is secured to the inner edge of the frame.

The mountings of these rollers 8 are best shown in Fig. 2, where the roller is carried by a U-shaped member 13, which slides within a sleeve 14, the axle of the roller 8, being guided by slots 15 in the sleeve. The member 13 may be retained within the sleeve by tongues 16 formed by bending inwardly the ends of the opposed side strips of the sleeve. 85 A coiled spring 17 is provided within the sleeve to serve as a cushion for the member 13, and to permit the roller 8 to roll smoothly in the groove 9, despite unevenness of depth of the groove. 90

By adjustment of the screw 11, the tension of the spring 17 may be increased or decreased to permit the roller to engage the groove 9, compensating for variations in distance between the strips 6 in different windows, or the roller may be retracted from the groove to permit removal of the screen from the casing. 95

In order to prevent binding between the rollers 8 and grooves 9, due to contraction or expansion of the strips 6 or wear upon the grooves, the rollers and grooves are so shaped that the bearing surface therebetween occurs only at or near the marginal edges of the grooves. By utilizing such construction, the roller cannot be pinched within the groove upon swelling of the wood, or by wearing upon the edges of the groove, and freedom of movement of the roller in the groove is substantially unaffected by any deposit of dirt or other substance in the bottom of the groove. One form of such 105 110 115

construction is illustrated in Fig. 3, where a V-shaped roller engages a V-shaped groove, the apex angle of the groove being more acute than that of the roller, so that an appreciable space exists at 18 between roller and groove. It has been found that satisfactory results are obtained when the apex angle of the V-shaped roller face is approximately 82°, and when the angle at the apex of the groove 9 is approximately 75°. Since this purpose may be served by any construction whereby the face of a roller meets the marginal edges of a groove in line contact, it is intended that the construction indicated shall be representative of any roller and groove with this characteristic.

I claim:

1. In combination with a window sash, a roller attached to the sash, and a window casing having an elongated groove receiving said roller for turning movement therein, the cross-sectional contour of the roller and groove being different so that the roller meets the marginal edges of the groove in longitudinal areas of narrow width, whereby freedom of movement of the roller in the groove is substantially unaffected by a deposit in the bottom of the groove.

2. In combination with a window sash, a roller attached to the sash, and a window casing having an elongate groove channeled therein to receive the roller, for turning movement, the roller being wider than the groove so that the roller bears on the sides of the groove, and the groove being sufficiently deep in the center to provide a space between the central portions of the roller and groove when the roller is in contact with the sides of the groove, whereby freedom of movement of the roller in the groove is substantially unaffected by a deposit in the bottom of the groove.

3. In combination with a window sash, a roller adjustably attached to the sash, a window casing having an elongate groove channeled therein for receiving the roller, and means for adjusting the position of the roller with respect to the groove to permit the roller to turn therein, the contacting surfaces of the roller and of the groove being beveled and the bevel of the roller surfaces being greater than that of the groove surfaces, whereby freedom of movement of the roller in the groove is substantially unaffected by unequal expansion or contraction of the roller and groove transversely of the groove.

4. In combination with a window sash, a roller carried by the sash, a window casing having an elongate groove channeled therein for receiving the roller and spring means associated with the roller for normally tensioning the roller against the groove, the contacting surfaces of the roller and of the groove being beveled and the bevel of the

roller surfaces being greater than that of the groove surfaces, whereby freedom of movement of the roller in the groove is substantially unaffected by unequal expansion or contraction of the roller and groove transversely of the groove.

5. In combination with a window sash, a roller adjustably mounted within a recess in the sash, a window casing having an elongate groove channeled therein for receiving the roller, and a spring normally tensioning the roller against the groove, the roller being wider than the groove and having a beveled surface bearing upon the sides of the groove, said groove being sufficiently deep in the center to provide a space between the central portions of the roller and groove when the roller is normally contacting with the sides of the groove, whereby freedom of movement of the roller in the groove is substantially unaffected by a deposit in the bottom of the groove or by unequal expansion or contraction of the roller and groove.

6. In combination with a window sash, a sleeve loosely mounted in a transverse recess of the sash, a carriage sliding in said sleeve, a roller carried by said carriage, a window casing having an elongate groove channeled therein for receiving the roller, a spring bearing on said carriage to tension the roller against the groove, and means for adjusting the position of the sleeve to increase or decrease the tension of the spring, the cross-sectional contour of the roller and groove being different so that the contacting surfaces between the roller and groove are defined by elongate areas of narrow width adjacent the edges of the groove, whereby freedom of movement of the roller in the groove is substantially unaffected by a deposit in the bottom of the groove or by unequal expansion or contraction of the roller and groove.

7. In combination with a window sash, a roller carried by the sash, a window casing having an elongate groove channeled therein for receiving the roller, a spring normally tensioning the roller against the groove, the contacting surfaces of the roller and of the groove being beveled and the bevel of the roller surfaces being greater than that of the groove surfaces, and a longitudinal lip projecting laterally from the outer side of the sash substantially to meet the window casing, whereby a tight closure between said sash and said casing is effected, and the position of the roller within the groove is secured against inward movement of the sash.

8. The combination with a window sash and a window casing spaced from the sash, of a roller carried by the sash, a window casing having an elongate groove channeled therein for receiving the roller, a spring associated with the roller normally

tensioning the roller against the groove, means for increasing or decreasing the tension of the spring upon the roller, and a longitudinal lip projecting from one edge of the sash, along the entire length of the outer face thereof, substantially to meet the outer face of said window casing flatwise, whereby the space between the sash and the

casing is closed, said lip also guiding the rollers within the groove, and securing the roller within the groove against inward movement of the sash.

Signed by me at Boston, Massachusetts, this second day of March, 1925.

FRED B. SAUNDERS.
